UNITED STATES PATENT OFFICE

GEORGE C. OLIN, OF CHICAGO, ILLINOIS, ASSIGNOR, BY MESNE ASSIGNMENTS, TO
SERVITOR MANUFACTURING COMPANY, INC., A CORPORATION OF ILLINOIS

SERVICE ATTACHMENT FOR FURNITURE

Application filed September 21, 1929. Serial No. 394,191.

My present invention relates to improvements in service attachments for furniture, and more particularly for card tables, although, as will hereafter be seen, my device may be easily attached to and detached from lamp standards, chairs, and, in fact, any piece of furniture which has a vertical member with which attachment may be made.

I am aware that brackets for attachment to table tops for the accommodation of smoking equipment have already been provided, but table tops are not uniform in design and dimension, and it is often undesirable to encumber any portion of the table-top when it is being actively employed.

I make my attachment to a table leg, or other vertical member of a piece of furniture, in a manner to secure all requisite stability and I have worked out the details of my structure so as to secure great simplicity and economy.

As will hereafter be seen, the base member of my structure comprises a shelf portion with provision for securely holding glasses and ash tray and a clamp. It is often desired to add other and more substantial refreshment and in connection with the base shelf and clamp I provide a tray convenient for coffee or sandwiches, which can be securely associated with the shelf and clamp and as easily detached therefrom.

I have attained the above objects by means of the structure illustrated in the accompanying drawings, in which—

Fig. 1 is a top plan of a structure embodying my invention;

Fig. 2 is a bottom plan thereof;

Fig. 3 is a section on line 3—3 of Fig. 2;

Fig. 4 is a perspective of the detachable tray; and

Fig. 5 is an elevation showing the tray assembled with the shelf.

Similar reference characters refer to similar parts throughout the several views.

In providing my service attachment I em-

ploy sheet metal of a suitable gauge, a bolt with a wing nut, eyelets or rivets and short lengths of wire of a suitable gauge. The shelf 10 is of substantially triangular form with broadly rounding corners. Adjacent each rounded corner is a perforation 11, and the exterior edges of the shelf and the perforations are preferably down-turned to provide depending edges 12.

Secured by eyelets 13, or rivets or other desired means, between the perforations in the shelf are right angled pieces 14 cut from bands or straps of sheet metal. The eyelets 13 are compressed only sufficiently firmly to hold the straps 14 dependably associated with the shelf 10 and to permit of a rotative or swivel action of the pieces 14 with reference to the shelf. Secured to the depending arms of the right angled pieces 14 by means of like eyelets or rivets 15 are clamp arms 16. These clamp arms extend horizontally in both directions from their points of attachment by the eyelets 15. The extension of these clamp arms 16 in one direction extends beyond the base edge of the shelf and these extended ends are bent outwardly, as at 17, and then inwardly, as at 18, to more readily engage a table leg or vertical furniture member. A bolt 19 extends between the arms 16, which, together with a wing nut 20, permits the convenient attachment and detachment of the clamp arms 16 with or from the furniture. The upper edges of the clamp arms are slotted or cut away, as at 16a, to permit of the passage through said cut away portions of the depending edge at the base of the shelf.

The extension of the clamp arms in the opposite direction, as at 21, gives me greater rigidity of support for the shelf and at the same time decreases strains which might otherwise fall upon the eyelets 15, and permits a wider opening of the clamping jaws. As will be seen in Fig. 2, the clamp members are curved outwardly from each other at 21 which permits me to give extended sup-

port of the shelf without limiting the opening of the clamp arms for the engagement of the furniture.

Glasses are made in standard and special sizes and for securing the glasses dependably I seat in the perforations 11 cups 22 of slightly tapering form provided with flanged lips 23. The flanged lips rest upon and engage the top of the shelf while the taper permits me to secure a close assembly between the shelf and the cups which will preclude rattling.

I prefer to make the cups which enter the perforations adjacent the base of the shelf somewhat deeper than the cup which enters the outer perforation in the shelf. When glasses are placed in these deeper cups it will require some ingenuity to inadvertently displace them. The shallow cup is more suitable for ashes, or matches, or whatever small articles it is desired to hold.

The tray combined and associated with the shelf and clamp is similar to other trays insofar as comprising a flat body portion 24 with an upstanding rim 25. I secure to the rim midway of its longitudinal dimension a handle or bail 26 and provided between the points of attachment of the bail and the ends of the tray two inwardly curved legs 27 of suitable gauge wire near each longitudinal edge. The tray is easily placed upon the shelf by slightly inclining the tray with the hooks of the legs engaging the depending edge of the base of the shelf which secures the tray from accidental disengagement from the shelf. By slightly inclining the tray it may be as easily removed from the shelf as it is assembled therewith.

Having described my invention what I claim as new and desire to secure by Letters Patent is:

1. A service attachment for furniture comprising a shelf portion of sheet material formed with depending edges, right angled straps pivoted in spaced relation with each other to the under side of said shelf portion, clamp arms secured to the outstanding portions of said right angled strap members and extending in both directions from their points of attachment, the inner ends of said clamp arms being curved away from each other and the other ends thereof being extended beyond said shelf and formed into clamping jaws, and means for adjustably securing said clamping jaws in desired relation.

2. A service attachment for furniture comprising a shelf portion of sheet material, right angled straps pivoted in spaced relation with each other to the under side of said shelf portion, clamp arms extended from the outstanding portions of said right angled strap members and extending in both directions from the points of attachment, said ends upon one side of the point of attachment being extended beyond said shelf and formed into

clamping jaws, and means for adjustably securing said clamping jaws in desired relation.

3. A service attachment for furniture comprising a shelf portion of sheet material, clamp arms pivoted in spaced relation with each other to the under side of said shelf portion and extending in both directions from the points of attachment, said ends upon one side of the point of attachment being extended beyond said shelf and formed into clamping jaws, and means for adjustably securing said clamping jaws in desired relation.

GEORGE C. OLIN.
